UNITED STATES PATENT OFFICE.

SAMUEL FERGUSON, OF SCHENECTADY, NEW YORK, ASSIGNOR TO GENERAL ELECTRIC COMPANY, A CORPORATION OF NEW YORK.

VAPOR ELECTRIC LAMP.

No. 924,975.

Specification of Letters Patent.

Patented June 15, 1909.

Application filed June 29, 1904. Serial No. 214,611.

To all whom it may concern:

Be it known that I, SAMUEL FERGUSON, a citizen of the United States, residing at Schenectady, county of Schenectady, State 5 of New York, have invented certain new and useful Improvements in Vapor Electric Lamps, of which the following is a specification.

My present invention relates more especially to a lantern or holder for mercury vapor or similar electric lamps, and comprises various details of construction, the novel features of which are pointed out with particularity in the appended claims.

15 The construction of the lamp itself will be better understood by reference to the following description taken in connection with the accompanying drawings, in which,

Figure 1 is a side elevation of the lamp; 20 Fig. 2 a view representing the manner of inserting the lamp proper in its holder; Fig. 3 a detail; and Fig. 4 a cross-sectional view of the lamp.

The lamp or illuminant in connection with 25 which my invention is particularly useful is that known as a mercury vapor lamp in which the light is produced by the passage of electric current through the instrumentality of mercury vapor in an exhausted envelop 30 or container of tubular or other convenient form. Such a lamp is indicated in outline at 1 in Fig. 1 and more clearly in side elevation at 1 in Fig. 4. The lamp is, of course, susceptible of many modifications. The 35 lamp shown by way of illustration, consists, however, of an exhausted glass tube 2 of convenient length, surmounted by a bulb 3 constituting a condensing chamber for the surplus mercury vapor produced during normal operation. The 40 electrodes of the lamp are two in number and are located at opposite ends of the container. The electrode at the top end of the lamp consists of a hollow cylinder 4 of artificial graphite or the like suspended by a conductor 5' the upper end of which is sealed 45 through the bulb 3 and is electrically connected to the metallic cap 6 cemented to the top of the bulb. The wire 5' is surrounded 50 by a protective tube 5 of glass, the lower end of which may flare slightly over the top of the electrode 4.

A filament 7 of carbon or other suitable material is suspended from the electrode 4 55 and extends down the tube 1 through cen-

tralizing guides 8, 9 and 10 into engagement with a body of mercury carried in the hollowed-out upper end of a plunger or float 11 of magnetic material. This plunger floats in a body of mercury 12 which 60 fills the lower end of the tube and which constitutes the lower, and in this case the negative, electrode of the lamp. The lower immersed body portion of the plunger moves in a contracted extension 13 of the tube and 65 is thereby held in a central position so that the cup in its upper end is always immediately under the lower end of the filament 7. The body of mercury 13 is connected by a suitable leading-in conductor with an external contact-making metal cap 14 cemented about the lower end of the contracted portion of the tube.

The lamp above described is carried by means of a lantern or holder, the transparent 75 walls of which are so fashioned as to produce a light distribution in which the light appears to emanate not as a band of light from the elongated tube but as a dispersed radiance. The body of the glass holder 80 appears to be filled with light. This effect is produced by making use of a holophane globe which consists, in the form shown, of a glass envelop provided with properly calculated dispersing prisms on the inside 85 thereof.

In the construction shown two globes, each of somewhat tapered form and practically identical with each other, are employed. These globes indicated at 15 and 16 are 90 placed with their larger ends together. These larger ends have outwardly projecting flanges and are encircled by two metal rings 17 and 18 fitting one into the other as shown more clearly in Fig. 4. These rings have inwardly 95 extending flanges 19 and 20 engaging the flanges of the globes 15 and 16. They are soldered or otherwise securely fastened together and thus strongly and permanently 100 secure the globes 15 and 16 together.

The support for the globes is provided by a circular sheet metal frame 20' pivotally carried by a bail or hanger 21. The pivots for this bail are indicated at 22 and 23 and are fastened to the sheet metal member 20'. 105 The upper end of the bail is provided with an insulating roller 24 by which the lamp is suspended from a suitable hook such as 25. The lamp globe is carried from the sheet metal member 20' by means of a perforated 110

metal cone 26, the lower end of which embraces the upper end of the globe 15 and is secured thereto by screws such as 27 and 28, while its upper end is spun into a central 5 opening in the circular member 20'. The walls of this opening are provided with an annular cushion 29 against which rests the bulb 3 of the lamp and by means of which the lamp is supported in the lantern. This 10 bulb 3 is surrounded by a protecting but ventilated casing 30 of woven wire carried by the member 20' and provided with a cover 31 fitting over the top of the same. This cover is provided with pins 32 and 33 which 15 respectively engage slots as 34 in the bail 21. The cover is also provided with a hole in one side thereof to be slipped over a hook 35 carried by the member 20'. When the cover is thus hooked over, the lantern hangs in the 20 position shown in Fig. 2. When in this position the mercury lamp may be readily inserted in the lantern as shown in this figure. The lamp tube is thus passed into the lantern until the bulb 3 rests upon the cushion 25 29. When in this position the lower end of the tube of the lamp projects beyond the lower end of the globe 16 and is then within the influence of a solenoid 36. This solenoid operates when energized to draw down the 30 magnetic plunger 11 in the lamp and thus start the latter into operation in a well understood manner. The solenoid consists of a coil of wire and is contained in a metal casing 37. This casing is securely fastened to a 35 skeleton metal ring 38, the upper end of which fastens over the lower flanged end of the globe 16. The openings in this ring provide entrance points for a cooling circulation of air up through the lantern. 40 The central tube 39 supported from the solenoid structure serves to center the lower end of the lamp and to support a part of the weight thereof. To secure electrical contact for the lower end of the lamp two spring 45 clips as at 40, carried by the solenoid structure but suitably insulated therefrom, press on opposite sides of the contact cap 14 on the lower end of the lamp. These clips are electrically connected to one terminal of the so- 50 lenoid winding, while the other terminal of

the winding is connected by a conductor 40' up through the globe of the lantern and out through the bushing 42. This bushing also carries a conductor 43 having a spring clip 44 engaging the cap 6 on the upper end of the lamp. These conductors 40' and 43 constitute the terminals of the lamp.

It will be evident from the foregoing description that numerous modifications in the construction of my invention may be made 60 without departing from the spirit thereof, for which reason I do not wish to be limited to the exact details shown and described.

What I claim as new and desire to secure by Letters Patent of the United States, is: 65

1. The combination of two light diffusing globes secured end to end, a vapor electric lamp mounted in said globes and provided with an armature, and a solenoid fastened to and carried by one of said globes and co- 70 operating with said armature.

2. The combination of a light diffusing globe, open at its lower end, a solenoid secured to said end by means permitting a circulation of air through the open end of 75 the globe, and spring clips carried by said solenoid.

3. The combination of a light diffusing globe, a lamp tube extending through said globe and projecting at either end, said lamp tube being provided with an armature, a solenoid surrounding one of the projecting ends, and protecting means surrounding the other projecting end.

4. The combination of a solenoid, a vapor 85 electric device having a contact-making cap, and a spring contact in the interior of said solenoid for engaging with said contact-making cap.

5. The combination of a solenoid, a vapor 90 electric device having a member projecting into said solenoid, a contact-making cap on said member, and a contact in said solenoid adapted to engage said contact-making cap.

In witness whereof I have hereunto set my 95 hand this 28th day of June, 1904.

SAMUEL FERGUSON.
